UNITED STATES PATENT OFFICE.

HENRY F. PRILLWITZ, OF CHICAGO, ILLINOIS.

ACETYLENE-GAS GENERATOR.

1,360,682.

Specification of Letters Patent. Patented Nov. 30, 1920.

Application filed June 18, 1919. Serial No. 305,029.

To all whom it may concern:

Be it known that I, HENRY F. PRILLWITZ, a citizen of the United States, residing at Chicago, in the county of Cook and State of Illinois, have invented new and useful Improvements in Acetylene-Gas Generators, of which the following is a specification.

This invention relates to acetylene gas generators in which the carbid is fed into the water in small quantities or charges, and its object is to provide a novel and improved carbid feed which is simple in construction and economical, and positive and efficient in operation. It is well known that carbid feeds with difficulty as it comes in lumps of all shapes and forms, and it is essential that all useless pivots, plates, levers, etc., be eliminated, as the carbid is apt to work in between such parts and prevent the apparatus from properly performing its work. This difficulty has been eliminated by providing a minimum number of pivots for freedom of action.

Another object of the invention is to prevent packing and clogging of carbid within the carbid hopper or container, thereby insuring a uniform and regular flow of carbid when the feeding means are in discharging position.

The invention also has for its object to provide a moisture-proof feeding means to prevent after-generation of gas which is a continuous loss, and also to prevent slaking and caking of carbid in the hopper or on the dumping pan which also results in a waste of gas and causes an irregular feed of carbid.

Other objects and advantages of the invention will be pointed out in the detailed description appearing hereinafter, and in order that the same may be better understood, reference is had to the accompanying drawings, forming a part of this specification.

In the drawings,

Figure 1 is a vertical section of the apparatus;

Fig. 2 is a sectional view of the carbid feed mechanism showing the same in discharging position;

Fig. 3 is a view similar to Fig. 2 showing, the feed-mechanism closed, and

Fig. 4 is a section on the line 4—4 of Fig. 3.

Referring specifically to the drawings, 5 denotes a carbid reservoir having a hopper

bottom 5^a provided with a contracted portion at the center open at the bottom and slightly to one side so that the carbid is not discharged straight down but sidewise. The 60 opposite side walls 5^b of the contracted portion are parallel, the rear wall 5^c follows the slope of the hopper bottom 5^a, whereas the front wall 5^d has an outward curve and terminates short of the bottom of the wall 65 5^c to leave the opening through which the carbid is discharged into a pan 6 positioned beneath said opening. This pan has a curved bottom and upstanding side walls 6^a, the latter being located on the outside of the 70 walls 5^b. The pan bottom extends at one end to the top of the side walls 6^a with a curve corresponding to the curvature of the wall 5^d, as shown at 6^b, to fit slidably on the outside of said wall. This end of the pan 75 has a hollow extension 7 adapted to be weighted as shown at 7^a. The other end of the pan is open, this end being the discharging end, and when the pan is in non-discharging position said end seats against an 80 inclined wall or stop plate 8 carried by and depending from the hopper bottom 5^a. This plate is faced with a tapered plug 8^a adapted to enter the pan end completely close the discharging end thereof as shown in Fig. 85 3. Beneath the plug 8^a, the plate 8 is faced with a gasket 8^b which projects beyond the edges of the plug, the edges of the pan engaging the projecting portions of the gasket to make a tight joint. The sides 6^a of the 90 pan carry packing strips 9 which slidably seat against the outer faces of the walls 5^b. It will therefore be seen that the pan 6, when in non-discharging position, completely seals the carbid outlet of the hopper against the 95 entrance of water or moisture, the curved end wall 6^b snugly fitting the wall 5^d as hereinbefore described. The carbid in the reservoir 5 is therefore completely shut off from moisture, and consequently prevented 100 from slaking or caking.

The pan 6 is pivoted on a shaft 10 passing across and through the walls 5^b and into the side walls 6^a of the pan. The pivot rod is made fast to the walls 6^a so that it 105 turns when the pan swings, and it has inside the walls 5^b a crank bend 10^a to which is attached an agitator rod 10^b extending upwardly into the hopper 5, whereby the carbid is stirred or agitated every time the 110 pan operates. The agitator rod also has bottom extensions 10^c which project into

the pan 6 so that when the latter swings down to discharging position these extensions move forward and prevent the carbid banking on the pan, thereby assuring a 5 uniform feed at all times. The upper end of the rod 10^b is loosely connected by a link 10^d to a support 10^e on the bottom of a conical shield 11 in the hopper 5 above the outlet of the latter. This shield helps 10 to carry the weight of the carbid and prevents it from bearing too hard on the pan 6 when the latter is in receiving and non-discharging position. The shield 11 is supported by legs 11^a from the wall of the 15 hopper bottom 5^a.

The side wall of the carbid reservoir 5 is continued below the hopper bottom 5^a, and its lower end is open and dips into the water in a tank 12, being supported in said 20 tank by legs 13. The carbid is discharged by the pan 6 into this water, and to facilitate the escape of the gas, the bottom of the reservoir wall which is immersed in the water has escape apertures 14.

25 The reservoir 5 is surrounded by a cylindrical wall 15 which is spaced from the wall of the tank 12 and is joined at the bottom to the latter as shown at 15^a. In the space between the wall 15 and the wall of the 30 tank 12 extends a gas bell 16, the usual water seal 16^a being provided. The gas rising from the water in the bottom of the tank 12 passes upwardly through the space between the reservoir 5 and the wall 15 and 35 then passes into the bell 16 as usual. The bell 16 has rollers 17 running on the inside of the wall of the tank 12, and serving to hold the bell properly centered and preventing it from sticking.

40 The carbid dumping pan 6 is operated by the rise and fall of the bell 16. As shown in Fig. 1, the bottom extension of the reservoir 5 supports a lever 18 having one end connected by a link 18^a to the pan, and to the other end of the lever is connected an upright slideable rod 18^b supported in a bearing 19 at the top of the reservoir. The rod is positioned at its upper end above the top of the reservoir so as to intercept the top 45 of the bell 16 when the latter has lowered a predetermined distance. The top of the bell, upon striking the upper end of the rod 18^b pushes said rod downwardly, whereupon through the lever 18 and the link 18^a the 50 pan 6 is swung down to dumping position as shown in Fig. 2. When the bell 16 again rises and releases the rod 18^b, the pan auto-

matically swings back to closed position as shown in Fig. 3, this action being produced by its counterweighted end 7, and the pan now refills.

To the top of the bell 16 is connected a flexible pipe 20 for conveying the gas to a service pipe 21, the latter also having a connection 21^a with the lower portion of the tank 12, so that when any moisture or 60 water gets in the pipe it will drain into the generating chamber. From the pipe 21 leads a pipe 22 which carries the gas to the place of use. The pipe 22 is provided with a valve 22^a which is closed when the apparatus is being replenished, in order to prevent the entry of air into the pipe line, which would cause flickering and buzzing of the lights. To the pipe 21 is also connected an exhaust valve 23 to let out all air 70 which may have gathered in the bell 16 or other parts of the apparatus after it has been replenished with water and carbid, and started.

The tank 12 has a cover 24 provided with 80 air-vent holes 25 to leave air in and out as the bell 16 lowers and rises.

It will be noted in Fig. 3 that the bottom of the pan 6 is curved in such a manner that when its discharge end seats against 85 the stop plate 8, and before arriving in this position, the bottom assumes a downward slope from this end, with the result that the carbid rolls down and away from the discharge end to preclude the possibility of the 90 carbid preventing the entrance of the plug 8^a.

A pump 26 is connected to the tank 12 for removal of the sludge accumulations.

I claim:

1. In an acetylene gas generator, a carbid 95 reservoir having an outlet, a swinging pan positioned over the outlet, a pivot rod for the pan movable therewith and extending across the outlet end of the reservoir, said rod having a crank, and a carbid agitator 100 connected to the crank and extending upwardly into the reservoir.

2. In an acetylene gas generator, a carbid reservoir having an outlet, a swinging pan positioned over the outlet, a pivot rod for 105 the pan movable therewith and extending across the outlet end of the reservoir, said rod having a crank, and a carbid agitator connected to the crank and extending downwardly into the pan and movable in the direction of the discharge end thereof.

In testimony whereof I affix my signature.

HENRY F. PRILLWITZ.
